Primary Examiner — Leanne Was-Englehart

(57) **CLAIM**

The ornamental design for a fence, as shown and described.

DESCRIPTION

FIG. 1 is a perspective view of a folding fence showing my new design.

FIG. 2 is a front view of a folding fence.

FIG. 3 is a rear view of a folding fence.

FIG. 4 is a left side view of a folding fence.

FIG. 5 is a right side view of a folding fence.

FIG. 6 is a top view of a folding fence.

FIG. 7 is a bottom view of a folding fence.

FIG. 8 is an enlarged detail view of area 8 shown in FIG. 1.

FIG. 9 is an enlarged detail view of area 9 shown in FIG. 1.

FIG. 10 is an enlarged detail view of area 10 shown in FIG. 1.

FIG. 11 is an enlarged detail view of area 11 shown in FIG. 1.

FIG. 12 is an enlarged detail view of area 12 shown in FIG. 1.

FIG. 13 is an enlarged detail view of area 13 shown in FIG. 1.

FIG. 14 is an enlarged detail view of area 14 shown in FIG. 1.

FIG. 15 is an enlarged detail view of area 15 shown in FIG. 1.

FIG. 16 is an enlarged detail view of area 16 shown in FIG. 1.

FIG. 17 is an enlarged detail view of area 17 shown in FIG. 1.

FIG. 18 is an enlarged detail view of area 18 shown in FIG. 1; and,

FIG. 19 is an enlarged detail view of area 19 shown in FIG. 1.

The broken lines depict portions of the fence that form no part of the claimed design.

1 Claim, 19 Drawing Sheets
